CLAIM

The ornamental design for a device to help install snow chains, as shown and described.

DESCRIPTION

FIG. 1 is a front perspective view of a device to help install snow chains showing my new design;

FIG. 2 is a top plan view thereof;

FIG. 3 is a right side elevation view thereof, the left side being a mirror image;

FIG. 4 is a bottom plan view thereof; and,

FIG. 5 is a rear elevation view.

Fig. 1

Fig. 2
